BOX HINGE

Clarence W. Cope, Dayton, Ohio, assignor to
Moraine Box Company, Dayton, Ohio, a corpora-
tion of Michigan

Application August 18, 1943, Serial No. 499,108

2 Claims. (Cl. 16—192)

This invention relates to hinges for connecting the side walls of a box or a crate together in such a manner that the crate or box can be factory assembled and shipped in a flat form to be subsequently arranged into a box-like structure after arriving at the point of use.

An object of the invention is to provide a simplified wire type of box hinge that will permit adjacent walls of a box to hinge 180° relative to one another, and which is constructed and arranged in a manner that a relatively accurate right angle box corner can be provided between adjacent wall members.

Another object of the invention is to provide a simplified wire type of hinge for a box or crate wherein the members comprising the hinge may be driven into adjacent corners of a box structure independently during preassembly of the box so that adjacent walls of the box structure may subsequently be brought into hinged relationship and a part of the hinge be bent downwardly against the box to retain the hinge members into assembled relationship.

Still another object of the invention is to provide a box hinge of the wire type that is constructed and arranged in a manner that the hinge elements can be driven into the corner of a box by the use of ordinary driving tools, such as a hammer.

Another object of the invention is to provide hinge members adapted to co-operate to form a hinge for a box or crate corner that are provided with interlocking loops that extend from the shank of the hinge elements so that the shank of the hinge elements can receive and absorb a hammer blow for driving the same into a box without any substantial distortion of the shape of the interlocking elements.

Still another object of the invention is to provide a hinge consisting of two members having shanks that are adapted to be driven into an object, and which are provided with interlocking means extending from the shanks in such a manner that they will not be distorted when a hammer is used to drive the shanks into an object.

Still another object of the invention is to provide a hinge in accordance with the foregoing object wherein the shank consists essentially of a nail and which may have a barbed surface or a helical screw surface.

Further objects and advantages will become apparent from the drawings and the following description.

In the drawings:

Figure 1 is a perspective cross sectional view

illustrating the assembled relationship of the hinge members in adjacent walls of a box or crate corner.

Figure 2 is a cross sectional view of adjacent walls of a box or crate wherein the hinge elements have been driven into the corners prior to assembly of the wall members together.

Figure 3 is a cross sectional view illustrating the assembly of the members shown in Figure 2 and with one of the hinge members bent downwardly after assembly to retain the hinge parts together.

Figure 4 is a cross sectional view of a box or crate illustrating the manner in which the hinge members can be driven into a box corner so that one wall of the corner will overlap an adjacent wall to permit direct nailing of the walls together.

Figure 5 is an elevational view of one of the hinge elements.

Figure 6 is an elevational view of the other of the hinge elements.

Figure 7 is a perspective cross sectional view of a modified hinge structure using a staple for one of the members and a single wire as the other hinge element.

Figure 8 is a cross sectional view of adjacent corner members of a box or crate illustrating the hinge elements shown in Figure 7 in position in the corners of the structure before assembly of the same.

Figure 9 is an elevational view of the staple element of the hinge structure illustrated in Figure 7.

Figure 10 is an elevational view of the hinge element that co-operates with the element illustrated in Figure 9.

In manufacturing crates, boxes and other items of similar nature, it is desirable that the boxes be shipped in a knocked-down condition to the destination and be subsequently assembled or arranged into a box arrangement for use in shipping various products. Such an arrangement permits the boxes to be shipped in much less space and thereby reducing shipping cost. Also, the boxes can be used a number of times because they can be knocked-down after the product has been shipped and be returned to the factory for reuse.

When manufacturing such boxes it is desirable that the four side walls of the box or crate shall be hinged together so that it is merely necessary to unfold the four walls and arrange them in substantially rectangular arrangement so that a top and bottom wall can be suitably nailed in engagement with the side walls. With a foldable

box structure of this type, it can be refolded when the top and bottom are removed and be returned for reuse.

One of the principal objects in providing a hinge structure for such boxes or crates is to permit folding of the walls of the box or crate so that they will lay in parallel adjacent relationship and the adjacent walls can be folded about a hinge connection to an extent of 180° whereby two adjacent walls may either lay in substantially planar alignment or can lay in face engagement with one another depending upon the direction in which the wall is folded. During process of manufacture of such folding boxes, or crates, it is desirable that each wall section be capable of manufacture as an individual unit and subsequent assembly of the walls can be arranged merely by interlocking hinge elements that are provided in the various independent wall sections.

In Figures 1 to 6, inclusive, there is illustrated a box hinge that consists of two hinge elements 10 and 15 that are provided with head structures adapted to interlock to provide a hinge for wall members to which they are attached.

The hinge element 10, illustrated in Figure 5, consists of a straight shank 11 that has a pointed end 12 suitable to permit driving of the shank 11 into a wood member. The shank 11 may be of the barbed type, or may have helical ribs thereon to insure a satisfactory hold in the wood member into which it has been driven. The upper end of the shank 11 is bent into the form of a U forming an eye 13 having an opening 14 therein. The U is closed on the shank 11 to prevent removal of an element from the opening 14 that may be inserted therein. The leg 16 of the U or eye 13 is formed at a right angle to the axis of the shank 11 so that the top surface 17 of the eye 13 will be normal to the axis of the shank 11.

With the hinge element 10 formed in the manner as illustrated in Figure 5, a hammer blow can be imparted upon the surface 17, acting as a head for the shank 11 of the hinge element 10 and if the hammer blow is square the entire shock of the blow will be taken by the shank 11 of the hinge element in an axial direction so that the hinge element 10 can be driven into a wood member in a manner similar to any nail. In fact, the shank 11 may be in the form of a nail. If desired, the eye 13 can be bent downwardly slightly as illustrated by the dot-dash line 18 (Fig. 5) to make the head of the shank 11 more prominent and thus insure that the eye 13 will not be deformed when the shank 11 is being driven into a wood member by means of the conventional hammer.

In Figure 6 the co-operating hinge element 15 is illustrated and consists of a shank 20 having a pointed end 21, the shank 20 being barbed or having a spiral groove therein in the same manner as referred to in connection with the shank 11. The upper end of the shank 20 is bent at a right angle to the axis of the shank to form an extending arm 22 normal to the axis of the shank 20 having an upper surface 23 that is disposed at least normal to the axis of the shank 20 but preferably, as illustrated in the drawings, is directed downwardly slightly relative to the axis of the shank 20 so as to provide a head portion 24 that may be given a blow by a hammer to drive the shank into a wood member. The tip of the extending arm 22 has a point 25 thereon that is adapted to be driven into the wood member to co-operate with the surface of the wood member and form an eye in a manner hereinafter de-

scribed that retains the hinge element 10 therein.

In Figure 2 the hinge elements 10 and 15 have been illustrated in position as driven into the corners of a pair of co-operating walls for a box or crate structure. The hinge element 10 is driven into the box or crate wall 26 at substantially a 45° angle relative to the inner surface 27 of the wall 26. Of course, this angle referred to has been arbitrarily selected but has been found to be the most desirable angle at which to drive the hinge element 10. The element 10 will be driven by the use of a conventional hammer striking the head surface 17 of the hinge element to drive the same into the wall 26 in the same manner as the nail. The tip end 28 of the hinge element 10 may then be knocked over to prevent withdrawal of the hinge element from the wall 26 if the end protrudes through the wall 26. The eye 13 will be in vertical planar alignment with the corner 29 of the wall 26.

Similarly, the hinge element 15 is driven into a wall member 30 at substantially a 45° angle to the inner surface 31, the tip end 32 being bent or knocked over to prevent withdrawal of the hinge element 15, if the end protrudes through the wall 30. As will be seen in Figure 2, the hinge element 15 has been driven into the wall 30 without causing any substantial deflection of the extending arm 22 because the hammer blows have been absorbed by the shank axially thereof in the same manner as though a nail was being driven. Also, the extending arm 22 is disposed at a right angle to the corner 33 of the wall 30 and at a right angle to the eye 13.

As illustrated in Figures 1 and 3 the walls 26 and 30 may now be brought into adjacent relationship so that the arm 22 projects through the eye 13. The tip end of the arm 22 is then imparted with a hammer blow to bend the same downwardly as illustrated in Figures 1 and 3 so that the end will lay against or drive into the surface 31 of the wall 30. It will thus be seen that the eye 13 cannot be removed from the hinge opening 34 provided by the co-operation of the arm 22 and the surface 31 of the wall 30 after the arm 22 has been driven into engagement therewith. It will be noted that the axis of the shank 20 of the hinge element 15 is disposed on one side of the axis of the shank 11 of the hinge element 10, and may be above or below the axis of the shank 11 depending upon whether the eye 13 points upwardly or downwardly. Therefore, in order to place the top surface of the wall 26 in planar alignment with the top surface of the wall 30 it will, of course, be necessary to drive the hinge element 15 into the corner 33 of the wall 30 at a slightly greater distance from the top edge of the wall 30 than is required for the point at which the hinge element 10 will be driven into the wall 26.

As many of the hinge elements as desired may be driven into the respective corners of the walls 26 and 30 to provide any number of hinge joints between these walls.

By referring to Figures 1 and 3 it will be apparent that the wall 30 can be hinged 130° about the corner 29 of the wall 26 so that the surface 31 of the wall 30 may lay in engagement with the surface 27 of the wall 26, or the respective wall members 26 and 30 may lay in planar alignment as illustrated by the dotted position of the wall 30. Also, with the hinge elements 10 and 15 being driven at the corners of the wall members 26 and 30 a relatively accurate and square box corner can be provided

between the wall members when they are exposed to 90° with respect to one another, as illustrated by the full line position of the members in Figure 3.

In Figure 4 there is illustrated a slightly modified arrangement of the manner in which the hinge elements 10 and 15 can be positioned with respect to the walls of a box or crate. In this modified arrangement the hinge element 10 has been driven into the surface 27a of the wall 26a a predetermined distance from the end 35 of the wall 26a. Also, the hinge element 15 has been driven into the surface 31a of the wall 30a a predetermined distance from the end 36 thereof, which latter distance is substantially greater than the former.

With the hinge members in position as illustrated in Figure 4, the wall 30a can overlap the end 35 of the wall 26a and lay in parallel engagement therewith so that a nail 37 can be driven through the wall 30a into the wall 26a to rigidly and securely hold the box together.

In the arrangement as previously illustrated with regard to Figure 3 the top and bottom wall of the box preferably holds the box walls in their desired arranged relationship.

The hinged joint illustrated in Figure 4 permits the wall 26a and 30a to lay in face engagement to permit folding of the wall members but the relative movement between the walls is limited to 90° as will be readily understood because of the overlapping end of the wall 30a.

In Figures 7 to 10, inclusive, there is illustrated a slightly modified arrangement of the hinge joint wherein the hinge joint consists of the hinge elements 40 and 45. The hinge element 40 consists of a wire that has been bent into the form of a U forming a staple member having the shanks 41 and 42. This member 40 is preformed into the shape illustrated before it is driven into a wood member, such as the corner of a box or crate.

The hinge element 45 is also constructed from a wire and consists of a straight shank 43 that has an arm 44 extending at a substantially right angle thereto which terminates in a downwardly extending arm portion 46 that is at substantially right angle to the arm 44.

The preformed wire hinge members 40 and 45 are driven by means of any suitable machine mechanism that is properly designed to prevent bending of the shanks of the hinge elements when being driven into a wood member.

In Figure 8 the hinge element 40 has been driven into a wall member 47 at the corner thereof so that the tip ends of the shanks 41 and 42 extend through the wall member in a manner that they can be subsequently bent over to prevent removal of the staple 40 from the wall member 47. The hinge element 45 has been driven into a wall member 48 in a manner similar to the hinge element, or staple 40, and has the end thereof bent over to prevent removal of the hinge element.

In Figure 8 it will be noted that the arms 44 and 46 are disposed relative to the inner surface 49 of the wall 48 to provide a substantially large

open area through which the head 50 of the staple 40 can pass to permit the arms 46 and 44 to pass through the head 50. The arm 44 will be given a hammer blow after assembly of the hinge elements together to cause the arm 46 to drive down into the surface 49 of the wall 48, as illustrated in Figure 7, to thereby form a closed eye with the wall 49 which prevents removal of the head 50 of the staple 40 therefrom.

From the foregoing description it will be apparent that the hinge provided by this invention greatly simplifies the assembly of wall members in hinged relationship, and that the hinge elements described with regard to Figures 1 to 6, inclusive, avoid the necessity of the use of any special machinery or devices to drive the hinge elements into the desired members. While the hinges disclosed and described herein constitute preferred forms of the invention, yet it will be readily understood that the device is capable of alteration without departing from the spirit of the invention, and that all such modifications as fall within the scope of the appended claims are intended to be included herein.

Having thus fully described my invention what I claim as new and desire to secure by Letters Patent is:

1. In a hinge for pivotally connecting the adjacent edges of a pair of wall members, a first hinge element having one end formed as a straight shank adapted to be driven into one of said wall members, and having its other end formed into a loop, one leg of the loop joining the shank at the end thereof at a right angle and the end of said loop abutting said shank at a point spaced from said right angle to close said loop, and a second hinge element having one end formed as a straight shank adapted to be driven into the other of said pair of wall members and having its other end formed as an integral arm joining said shank at substantially right angles to form a hook passing through the closed loop of said first hinge element and bent into engagement with the wall member, said arm lying in a plane through the axis of the shank of said second hinge element.

2. In a hinge for pivotally connecting the adjacent edges of a pair of wall members, a first hinge element having one end formed as a straight shank adapted to be driven into one of said wall members, and having its other end formed into a loop, one leg of the loop joining the shank at the end thereof at a right angle and the end of said loop abutting said shank at a point spaced from said right angle to close said loop, and a second hinge element having one end formed as a straight shank adapted to be driven into the other of said pair of wall members and having its other end formed as an integral arm joining said shank at substantially right angles to form a hook passing through the closed loop of said first hinge element and bent into engagement with the wall member, said arm lying in a plane through the axis of the shank of said second hinge element, and each of said right angle portions forming an impact surface.

CLARENCE W. COYE.
